MOUNTING FOR CARDS, PHOTOGRAPHS,
AND THE LIKE

Albert A. Ainsworth, Ossining, N. Y.

Application October 24, 1938, Serial No. 236,779

6 Claims. (Cl. 129—19)

The invention relates to the art of mounting and filing papers, autographs, clippings, samples, scrap book entries and other strips or articles of paper, cloth or other fabric or material and more particularly relatively stiff articles such as cards or photographs, and is intended primarily as an improvement on the invention set forth in my prior Patent No. 1,461,570 dated July 10, 1923, and Patent No. 1,862,450 dated June 7, 1932. The present application is a continuation-in-part of my prior application Serial No. 30,616 filed July 10, 1935 now Patent No. 2,142,261, dated January 3, 1939, which in turn is a continuation-in-part of an earlier application Serial No. 699,780 filed November 25, 1933, now Patent No. 2,038,468 dated April 21, 1936, the entire disclosures of which are hereby incorporated by reference as part of the disclosure of the present application.

In common with my Patent No. 1,862,450, I prefer to employ a backing or folder of comparatively stiff material having one or more strips of tough, flexible material secured to the backing and having tongues or tabs for adhesively retaining the slips or articles to be filed, and the broad object of the invention is accordingly to improve and simplify the mountings disclosed in said patent and to furnish quick, easy, economical and permanent methods of mountings cards, photographs, snapshots, office data and the like in a convenient overlapping manner so that a portion of each article when mounted is always visible, and also so that when turned back the contents written or printed on one or both sides of the mounted article are clearly visible.

A more specific object of the invention is to improve the form of tongues or tabs employed in the mounting so as to give additional mounting strength. A further object is to provide means for securing perfect alignment of the cards, photos, etc., without the necessary use of guide lines. Another specific object of the invention is to provide, in combination with a backing, a plurality of separate and individual mounting strips, each adapted to carry a single card or the like, such strips with the cards mounted thereon being arranged in battery upon the backing in such a manner that the cards overlap one another with portions of each card visible. A further object is to provide a mounting strip with tongues which are easily folded back. Still another object is to provide a cheap and economical method for forming a plurality of the individual strips from a sheet of material with minimum loss of such material.

Other objects of the invention will be apparent

from the accompanying drawings and the following detailed description, in which are set forth for the purpose of illustration various specific embodiments of the inventive thought involved, it being understood that these specific embodiments are intended as illustrative only and not as limiting the invention.

In the drawings:

Fig. 1 shows an open album or other book having cards assembled in overlapping order by means of a filing or mounting strip on one face and a filing strip on the other to which cards are adapted to be secured and mounted in overlapping order, one card being shown in the process of being mounted.

Fig. 2 is a rear view showing a modified form of filing or mounting strip which may be used with the album shown in Fig. 1 or with any other suitable backing.

Fig. 3 is a rear view showing a further modified filing strip to be mounted upon a suitable backing.

Fig. 4 is a rear view showing still another form of filing strip.

Fig. 5 shows a filing strip comprising a single row of tongues.

Fig. 6 shows an open album on one face of which the filing strip of Fig. 3 is applied and on the other face the filing strip of Fig. 4 is mounted.

Fig. 7 shows an open album provided with guide lines to assist in aligning individual strips, upon one page of which the filing strips of Fig. 8 are applied and on the other face the filing strips of Fig. 9.

Fig. 8 shows individual filing strips which may be cut from the continuous strip of Fig. 4.

Fig. 9 shows individual filing strips which may be cut from the continuous strip of Fig. 5.

Fig. 10 shows another form of individual filing strip.

Fig. 11 shows still another form.

Fig. 12 shows a further modification.

Fig. 13 shows still another form.

Figs. 14 and 15 indicate two additional modifications.

Figs. 16, 17 and 18 indicate steps in a method of forming individual filing strips from a suitable blank.

According to the preferred embodiment of my invention a suitable backing sheet 10 of comparatively stiff material is employed which may constitute one or both covers or pages of an album or other filing folder such as is referred to for example in my Patent No. 2,038,468 and in my co-pending application Serial No. 30,616 now Patent No. 2,142,261 dated January 3, 1939. The back-

ing sheet is shown in Figs. 1, 6 and 7 of the present drawings, but is adapted for use with each of the forms of mounting strips herein disclosed.

To this backing a mounting or filing strip 11 of relatively tough flexible material such as cloth, paper, or the like is adapted to be applied, which strip may be of the general type disclosed and claimed in my Patent No. 1,862,450 dated June 7, 1932. This strip is preferably provided with an adhesive gum coating on its rear surface, the front surface being preferably non-adhesive. The strip is shown as provided with a plurality of transverse incisions 12 forming upturned tabs or tongues 13 integral with the strip. Each tab or tongue being formed from strip 11 has on its rear side a portion of the gum coating which covers the rear side of the strip.

These tabs are adapted to be bent outwardly from the back for the purpose of mounting cards, photographs or the like 14 and to facilitate such bending operation transverse score lines 15 may be applied preferably at the time the tabs are formed. These score lines may extend entirely across the strip or only between the incisions as may be preferred.

In mounting a card upon the filing strip the lower edge of the card is inserted beneath the tab or tabs 13 as shown at the right of Fig. 1 and adhesively secured thereto. The card may then be turned down about the tab or tabs to the position shown at the left of Fig. 1. Owing to the relative stiffness of the card as compared with the flexibility of the tabs the entire bending operation will take place within the tab itself as distinguished from the arrangement shown in my prior Patent No. 1,862,450 wherein relatively flexible slips are contemplated as compared with the stiff cards preferably employed according to the present invention.

It will be obvious that many forms of hinges, tabs or tongues and many arrangements of hinges, tabs or tongues upon the filing strip and upon the backing may be employed within the scope of my invention. In Fig. 1, for example, I have shown a very effective arrangement of tabs which is designed to hold the cards or the like firmly in position. In this arrangement each card is held by two upwardly extending tabs 13 and an intermediate tab 16 which is adapted to engage the opposite side of the card from that to which the tabs 13 are secured. As shown the tabs 13 are arranged in two outer rows with the tabs 16 in an intermediate vertical row. Tabs 13 are shown as of inverted V form and the tip of each lower tab extends above the line connecting the ends of the incision 12 which forms the tab next above it.

In Fig. 2 there is shown a rear view of a slightly modified form of filing strip which is to be adapted to any suitable backing such as that shown in Figs. 1, 6 or 7. In this form two vertical rows of tabs 18, 18 are shown, the tabs all extending upwardly and the intermediate row of downwardly extending tabs being omitted. The backing sheet may be gummed at 19 on the rear surface as indicated and cards are adapted to be applied in the same manner as indicated and described in connection with Fig. 1.

In Fig. 3 the filing strip is provided with a plurality of transverse rows of V shaped tongues, each row including three tongues all pointing upwardly. The strip including the tongues is gummed at 19 on the back and is adapted to be applied to a suitable backing and cards secured to the tabs or tongues in the manner de-

scribed in connection with Figs. 1 and 2. It will be noted that the strips are perforated so that the rows or tongues may be separated and applied individually instead of as a single strip. When a plurality of such individual filing strips 5 are mounted upon a backing and cards applied thereto the arrangement is the same as though the complete strip containing a plurality of rows of tongues were applied as a unit, the individual strips being applied so as to form substantially 10 a continuous sheet.

A very similar construction is shown in Fig. 4 wherein the tongues or tabs 20 are formed by curved rather than straight incisions and only two tabs are shown in a single lateral row. These 15 rows of tabs or tongues are adapted to be separated along lines 21 and applied as units as indicated in Figs. 7 and 8.

If desired each card may be mounted by means of a single tongue instead of by means of a plurality of tongues. Thus in Figs. 2, 3 and 4 the rows of tongues may be sufficiently separated laterally so that each tongue will suffice to mount a card. In Fig. 5 there is shown a strip wherein a single tongue 20 only is employed instead of 25 a plurality of tongues. This strip may be separated along lines 22, 22 into individual mounting units as illustrated in Figs. 7 and 9, or may be separated along a line intermediate the tongues to form an individual mounting such as is shown in 30 Fig. 15.

If desired the backing may be provided with guide lines 23 and 24 to facilitate mounting of the filing strips. One such arrangement is shown in Fig. 6. On the page at the left of the figure 35 the form of filing strip shown in Fig. 3 is illustrated as applied by means of the guide lines and on the page at the right of the strip the form of mounting strip shown in Fig. 4 is illustrated. The filing strips may be furnished in 40 convenient sizes to correspond with the guide lines.

In Fig. 7 the backing is shown as provided with ruled vertical and horizontal lines 25 and 26 to facilitate mounting the individual strips, the arrangement being similar to that shown in Fig. 45 12 of Patent No. 2,038,468 dated April 21, 1936, and in Fig. 1 of my co-pending application Serial No. 30,616 now Patent No. 2,142,261 dated January 3, 1939. At the left of this figure the individual units illustrated in Fig. 8 are shown applied and at the right the units illustrated in Fig. 9 are shown applied. Obviously when properly applied the individual strips make up a composite assembly which constitutes a substantially 55 continuous filing strip mounted upon the backing similar to what is illustrated in Fig. 6.

Various forms of individual strips may be employed. Those shown in Fig. 8 may be formed from the composite strip shown in Fig. 4. Those 60 in Fig. 9 may be formed from the composite strip shown in Fig. 5, and that shown in Fig. 11 may be formed from the composite strip shown in Fig. 3. The filing strip shown in Fig. 11 is the same as that illustrated in Fig. 14 of my Patent 65 No. 2,038,468 which is shown assembled in Fig. 12 of that patent. Other forms of strips are shown in Figs. 10 and 12 of the present application which correspond with those shown in Figs. 7 and 4 respectively of my application Serial No. 30,616 now Patent No. 2,142,261. In Fig. 13 an individual strip containing two upwardly pointing tongues 13 and a downwardly pointing tongue 16 such as is illustrated in Fig. 1 is shown.

In Fig. 14 a simple form of mounting strip is 75

illustrated which is merely a rectangular strip preferably gummed on one side and unguammed on the other. The strip is divided into two halves 30 and 31 by means of a score line 32. The lower 5 half is adapted to be secured to a backing leaving the other half free for the mounting of a suitable card, after which the card is turned over about the hinge line 32. Where a plurality of these strips are mounted on a backing and suit- 10 ably assembled by the aid of scorelines such as shown for example in Fig. 7 it will be obvious that the mounted cards will overlap one another in a manner similar to that shown in Fig. 1.

In Fig. 15 a unit mounting having a single 15 tongue is shown such a mounting strip being readily formed from composite strips similar to that shown in Fig. 5, the individual strips being cut out along transverse lines extending midway between the tongues. When a plurality of such 20 mounts are applied contiguous to one another the assembly constitutes a substantially continuous strip, and the cards applied to the individual tongues will overlap one another as shown in Fig. 1.

25 It has been shown that individual mounting strips may be separated from vertical rows of strips. Figs. 16, 17 and 18 illustrate an efficient manner by which a plurality of individual mounting strips such as shown in Fig. 10 may be formed 30 from a single strip 40. This strip may if desired be first gummed on one side, then scored and cut as illustrated in Fig. 17, after which the individual strips may be separated as illustrated in Fig. 18.

35 Obviously any of the strips herein shown are adapted to be applied to any of the backings and cards applied to the strips in the manner previously described.

40 While a number of different forms and embodiments of my invention have been disclosed it is apparent that further modifications and variations may be resorted to without departing from the spirit of the invention.

45 It will be noted that the weakened, perforated or scored lines on the strip hinges serve to facilitate the bending back of the hinges, and where two or more hinges are used in horizontal formation, the bases of all of the hinges are in alignment and thereby eliminate the necessity for 50 using printed lines on the backing or measuring the distances when filing or mounting is done.

I claim:

1. A mount for cards and the like composed of a mounting strip of flexible sheet material adapted to consecutively mount a plurality of cards in overlapping relation to each other on a backing member, said strip having a gum coating 5 on its rear side, a non-adhesive front side, and a plurality of transverse incisions defining free ends of tabs integral with the strip, each tab having on one side a portion of the gum coating, and a non-adhesive opposite side, said tabs being 10 bent outward from the strip and folded against the non-adhesive front side thereof with its non-adhesive side inward, the portions of the gum coating on the tabs being exposed at the outer side of the strip, the gummed side of the strip 15 being attachable to a backing member, and cards or the like being attachable to the gummed sides of the tabs so that they lie in overlapped relation on the outer side of the strip and the backing member. 20

2. A mount for cards and the like comprising, in combination, a backing member, a flexible body of sheet material having a gum coating on and co-extensive with its rear side, a non-adhesive outer side, and a transverse incision defining a free end of a tab integral with said body, said tab being bent outward from the body and folded against the non-adhesive side of the body with its non-adhesive side inward and facing the non-adhesive outer side of the body, and its 30 gummed side outward, and exposed, the gummed inner side of the body being attachable to the backing member, and a card or the like being attachable to the exposed gummed side of the tab. 35

3. A mount as specified by claim 1, the strip being provided with scores or creases extending between the ends of the incisions. 40

4. A mount as specified by claim 2, the body being provided with a score or crease extending between the ends of its incisions. 45

5. A mount as set forth in claim 1, wherein the mounting strip is perforated at intervals so as to form a plurality of individual filing strips adapted to be arranged one beneath the other upon the backing. 50

6. A mount as set forth in claim 1, wherein a plurality of card holding tabs are arranged in rows, and one row of tabs is adapted to engage the cards on the opposite face from the others. 55

ALBERT A. AINSWORTH.
